Primary Examiner—Ian Simmons
Assistant Examiner—Melanie Levy(57) **CLAIM**

The ornamental design for a compression sleeve, as shown.

DESCRIPTION

FIG. 1 is a top plan view of a compression sleeve in accordance with the present invention;

FIG. 2 is a bottom plan view of the compression sleeve of FIG. 1;

FIG. 3 is a side plan view of the compression sleeve of FIG. 1; and,

FIG. 4 is a side plan view of the compression sleeve of FIG. 1.
